Henry Orenstein, 136 Lakeside Ave.,
Verona, N.J. 07044

Filed Feb. 10, 1975, Ser. No. 548,643

Term of patent 14 years

Int. Cl. D21—01

U.S. Cl. D34—2 R

FIG. 1

FIG. 2

FIG. 3

FIG. 4

FIG. 5

FIG. 1 is a front elevational view of a toy pig figure showing my new design;

FIG. 2 is a right side view thereof;

FIG. 3 is a rear view thereof;

FIG. 4 is a top plan view thereof; and

FIG. 5 is a bottom view thereof.

The left side view, while not illustrated, is a mirror image of the right side view illustrated in FIG. 2.

I claim:

The ornamental design for a toy pig figure, as shown and described.
